UNITED STATES PATENT OFFICE.

HANS KELLER, OF LUDWIGSHAFEN-ON-THE-RHINE, GERMANY, ASSIGNOR TO BADISCHE ANILIN & SODA FABRIK, OF LUDWIGSHAFEN-ON-THE-RHINE, GERMANY, A CORPORATION OF BADEN.

PRODUCING HYDROGEN.

1,286,650.

Specification of Letters Patent.

Patented Dec. 3, 1918.

Application filed April 19, 1913. Serial No. 762,246.

To all whom it may concern:

Be it known that I, HANS KELLER, a citizen of the German Empire, residing at Ludwigshafen-on-the-Rhine, Germany, have invented new and useful Improvements in Producing Hydrogen, of which the following is a specification.

It is known that hydrogen can be obtained by passing steam over iron at a raised temperature and that iron oxid thus formed can be reduced by means of suitable gases into metallic iron, or ferrous oxid, whereupon the treatment with steam is repeated and the process becomes cyclic. Various forms of iron have been employed for this purpose, such for instance as iron turnings, iron shavings, and iron sponge, but the forms hitherto employed have not proved completely suitable, as after a time the surface of the iron loses its full activity.

I have now found that hydrogen can be very advantageously obtained according to the aforesaid process by employing a porous, or spongy, iron, which has been obtained from iron ore, or iron oxid, of any origin by surrounding it with carbon and transmitting heat through the carbon to the said iron ore or iron oxid. Such a product is that known as Swedish iron sponge and can be obtained according to the specification of British Patent No. 1134/11. Other forms of iron with similar properties which have been obtained by the method described can also be employed when carrying out this invention.

The production of hydrogen with the aid of said porous or spongy iron is carried out by passing steam over the iron at a raised temperature, whereafter the iron oxid formed can be retransformed into the metallic spongy iron by passing a reducing gas over it; these two steps then can be repeated alternately and they can both be carried out in the known or any suitable manner.

The aforesaid iron sponge is characterized by the fact that, after being employed for a short time in the production of hydrogen, it becomes very hard, but in spite of this remains very porous and reactionable.

An apparatus suitable for carrying out the process of my invention is illustrated in the accompanying drawings. In these, Figure 1 represents a vertical section of the apparatus and Fig. 2 is a plan view of the

same. Similar letters and figures in the drawings refer to similar parts.

In the drawings, *b* is the reaction or generator furnace, *a* and *c* are heat regenerators, each being well isolated against loss of heat. The regenerators comprise a combustion channel 1 and 21 and a net work of fireproof bricks 2 and 22. The spongy iron which has been previously prepared as described by embedding iron oxid in carbon and then transmitting heat through the carbon to the said iron oxid, is contained in the shaft 3 of the reaction furnace, while *d* and *e* are three-way valves capable of being cooled. The method of working may be, for instance, as follows:

The regenerators are first heated to a high temperature by burning in them a mixture of generator gas or water-gas with air, while the waste gases pass, through the valves 8 and 9, into the chimney. As soon as the desired temperature is attained, one of the valves leading to the chimney, for instance 8, is closed and, after opening valve 10, reducing gas is first blown through the apparatus in the directions 2—1—12—14—18—3—17—13—21—22—9 or 2—1—12—16—3—19—15—13—21—22—9, whereby the spongy iron in the furnace *b* is heated, an alternate passing of the gases from above and from below through the furnace further causing the iron to attain a fairly uniform temperature. The reducing gases leaving the furnace are mixed with the necessary amount of air from 5 and burnt in *c*. When the temperature in the regenerator *a* diminishes, the gases are passed through the apparatus in the reverse direction, that is to say, from 11 to 8, so that the regenerator *a* is again raised to a high temperature. If desired, however, the fall of temperature in the regenerator can be diminished by adding a small quantity of air to the reduction gases, whereupon an equivalent small quantity of reducing gas is burnt in the regenerator. When the necessary temperature in the reaction furnace is attained, assuming the gases were last passed in the direction 10 to 9, the valve 10 is closed and steam is passed through the valve 23, so as to wash out the whole apparatus with steam or hydrogen, which is formed by the action of the steam upon the heated spongy iron 3, preferably allowing the steam to en-

2

ter the shaft 3 of the generator furnace from above; the impure hydrogen which is first formed is mixed with air from 5 and burnt in the combustion chamber 21 of the 5 regenerator *c*. The three-way valve *d* is then so operated that the steam passes through 16 up into 3 and the valve 25 is opened and the valve 13 is closed, whereupon the hydrogen passes off in a pure state 10 through 25 to the gasometer. When the oxidation period is over, the reaction mass is again reduced by passing reducing gases through the apparatus in the direction 10 to 9 as above described. The valves 4, 6, 7 and 15 24 are for use in supplying combustible gas, air or steam to the regenerators, to which they are respectively attached. If after a series of oxidation and reduction periods, the temperature in *a* has sunk too low, the 20 gases are passed in the reverse direction, so that the regenerator *c*, which in the meantime has attained a high temperature, gives up its heat to the reducing gases and the steam, while the temperature of the other 25 regenerator is being raised again by burn-

ing the excess of reducing gases therein, either alone or with fresh gas in addition.

The drawing however illustrates only one of the numerous apparatus capable of being employed for carrying out the present invention and for instance, the reaction furnace can also be directly heated. The invention is in no way confined to the use of any particular form of the apparatus. 30

Now what I claim is:—

The cyclic process of producing hydrogen by alternately passing steam and a reducing gas mixture at a raised temperature over spongy iron which has been produced by embedding an oxy-compound of iron in carbon and transmitting heat through the carbon to the said oxy-compound of iron. 40

In testimony whereof I have hereunto set my hand in the presence of two subscribing witnesses.

DR. HANS KELLER.
